Inventor
S. J. Colton,
By *Clarence O'Brien*
Attorney

UNITED STATES PATENT OFFICE.

STANLEY J. COLTON, OF BINFORD, NORTH DAKOTA.

TRACE CARRIER.

Application filed September 15, 1926. Serial No. 135,620.

This invention relates to an improved trace carrier; that is, a small contrivance to hold the ends or "tugs" upon the back of the horse temporarily when not in use to 5 keep the same from dragging on the ground.

The invention has more particular reference to an exceptionally simple and inexpensive article of manufacture, somewhat in the 10 form of a buckle adapted to be associated with a breeching strap on a breeching harness.

The particular details of construction, and advantages derived from their use will be 15 come apparent from the following description and drawings.

In the drawings:—

Figure 1 is a side view of a portion of a conventional form of harness showing the 20 device applied to the breeching strap.

Fig. 2 is a view of a fragmentary portion of said strap showing the invention more in detail and more particularly how it is applied.

25 Fig. 3 is a side view of Fig. 2.

In the drawings, the reference character 1 designates a strap constituting a part of a conventional form of harness, which strap passes around the back of the legs of the 30 animal. The breeching straps which are associated therewith are designated by the reference characters 2 and 3. The reference character 4 designates a portion of one of the straps of a trace which includes the customary chain 5 and the cockeye or ring 6. It is this trace with which the invention, 35 generally designated by the reference character 7, is associated.

The invention comprises a metal body 8 40 having its opposite ends bent to form hooks 9 and 10. It will be noticed that the curvature of the bill of the hook 10 is somewhat pronounced to facilitate connection of the cockeye 6. At the juncture of the body portion 45 and the base portions of the hooks 9 and 10, are transverse slots 11 of a size to permit free passage of the breeching strap 2, which passes through them and against the inner side of the body 8 as represented in 50 Figs. 2 and 3.

A stud 12 is provided and extends through an opening in the breech strap to prevent

slippage of the device on said strap. Attached at one end to the hook 9 is a spring latch 13 which extends down and cooperates 55 with the bill of the hook 10. It will be noticed, however, that the extremity of this latch is curved as at 14 and extends beyond said bill and forms a seat for the ring 6 when it is disengaged.

In practice the device is placed upon the lazy strap or the breeching strap as shown in Fig. 1, the stud 12 being passed through the opening in said strap to hold the device in set position. The latch is disposed on 60 the outside so that when the trace is not in use, the ring 6 on the free end of the chain may be snapped into the hook 10 and held by the spring latch 13. When removing the same, the ring is placed in the seat 14 and 65 pushed inwardly, thus providing clearance between the latch and the bill of the hook and facilitating disengagement.

From the foregoing description and drawings, it will be seen that I have evolved 70 and produced a simple and inexpensive contrivance which may be applied to a conventional harness structure without requiring alterations of the latter, and the same serving as a temporary hanger for the trace so 75 that it will not drag on the ground when it is not in use. The particular formation of the respective details of the device make it compact and convenient and highly efficient 80 in action.

It is believed that a clear understanding 85 of the invention and the construction and its advantages will be had from the foregoing. Consequently, a more lengthy description 90 is thought unnecessary.

While the preferred embodiment of the invention has been specifically described and shown in the drawings, it is to be understood that minor changes in shape, size, and arrangement of parts may be resorted to so 95 long as no departure is made from the appended claim.

Having thus described my invention, what I claim as new is:—

As a new product of manufacture, a trace 100 carrier comprising a single body having its opposite ends bent into hooked formation, the bills of the hooks being disposed somewhat in the same plane, one hook forming a

keeper for a trace cockeye, the body being formed at its points of connection with the hooks with slots for passage of a carrying strap, being also provided with a central angularly disposed stud for passage through an opening in said strap, a spring latch connected to the free end portion of one of the

hooks and extending downwardly beyond the bill of said keeper hook, the extending portion being curved longitudinally to form a seat for reception of said cockeye to facilitate disconnection of the latter.

In testimony whereof I affix my signature.

STANLEY J. COLTON.
